COAT SHIELD

Hugh G. Dugan, Hinsdale, Ill.

Application March 31, 1933, Serial No. 663,693

10 Claims.

(Cl. 2—53)

The shield of the present invention is intended primarily, though not exclusively, for use as a shield for men's coats, and is intended to be fitted into the arm pit of a coat or similar garment for the purpose of preventing the transmission of perspiration to the coat and of permitting ventilation through the shield in the vicinity of the arm pit.

With the above end in view, the shield is preferably molded of rubber or rubberlike non-absorptive material in such a way as to give to the shield a permanent arch formation in cross section, which renders the shield self-sustaining at the arch or ridge between the inner and outer flaps, and provides for more perfect ventilation which tends to promote the comfort of the wearer.

Further objects and details of the invention will appear from the description thereof in conjunction with the accompanying drawing, where-

in,—

Figure 1 is a side elevation of a simplified form of construction;

Fig. 2 is a cross sectional elevation through the center thereof;

Fig. 3 is a side elevation of a ribbed form of construction;

Fig. 4 is a sectional elevation through the center thereof;

Fig. 5 is a side elevation of a form similar to that of Figs. 3 and 4, with the addition of hard inserts in the ribs;

Fig. 6 is a cross sectional view of the same; and

Fig. 7 is a cross sectional view of a slightly modified form of construction.

In all forms of construction the body of the shield is of arch shaped configuration comprising side flaps 10 and a connecting arch portion 11, giving to the shield as a whole the general form of a saddle, elevated at the ends and depressed in the center, to conform to the configuration of the coat or other garment at the point where the sleeve unites with the body of the garment beneath the arm pit.

The shield as a whole is of integral formation and is preferably molded from rubber or other rubberlike moisture proof material, and it is preferred to have the material slightly thickened on the arch so as to render this portion of the shield self-sustaining against collapse or creasing, and so as to maintain the intended curvature of the arch under all ordinary conditions.

The side flaps of the shield are relatively thin and flexible to easily conform to the movements of the wearer, and the curvature of the arch portion serves to hold the two flaps properly distended to a degree sufficient to easily bridge over the ridge at the juncture of the sleeve with the body of the garment.

In order to promote the circulation of air through the shield without permitting the ab-

sorption of moisture which would occur if an absorbent material were employed, the side flaps of the shield and also the arch thereof are provided with perforations 12 preferably arranged in straight vertically extending rows.

65

The shield is held in place within the garment by the provision of pairs of snap fasteners 13—13 and 14—14 on the two side flaps near the lower edges thereof, which are adapted to co-operate with snap members suitably positioned on the garment, and further attaching means in the form of snap fasteners 15—15 are provided at the upper ends of the arch, which arrangement permits the shield to be readily secured in place within the coat or other garment and held 70 against displacement as the arm of the wearer is slipped into the sleeve of the coat.

75

In Figs. 3 and 4, I have illustrated a modification which consists in the addition of continuously extending outstanding vertical parallel ribs 80 16 which gradually increase in height toward and over the arch and lie intermediate the lines of perforations and which are integrally molded with the remainder of the shield. The provision of the ribs is desirable in order to reinforce the 85 shield against collapse and to render it self-sustaining to a sufficient degree to maintain the intended arch formation; and the provision of the ribs also serves to afford grooves or channels into which the perforations open and which serve 90 in conjunction therewith to more completely provide for ventilation through the shield. Save for the addition of the ribs, the shield of Figs. 3 and 4 is similar in all respects to the construction first described.

95

In Figs. 5 and 6, I have shown a construction which is similar in all respects to that of Figs. 3 and 4 save for the addition of inserts 17 of hard rubber, celluloid or the like, which are fitted into the ribs and constitute in effect the arch portions thereof, being each configured to constitute an unbroken continuation of the rib into which it is fitted. The inserts are of arcuate formation, and each is provided with an inwardly expanding lug or dowel 18, which is entered through the material of the body of the shield, or around which the body of the shield may be molded so as to prevent removal of the inserts. It is preferred to have the inserts located slightly off center above the arch so as to present a preponderance of surface toward that side of the shield which overlaps the body of the coat or other garment, in order to provide a smooth non-frictional surface over which the inner garments of the wearer may slip when inserting the arm into the sleeve of the coat. The inserts, which are relatively stiff and smooth, serve both to reinforce the shield at the arch and to provide a smooth non-frictional surface throughout the 100 110 115 120

entire length of the shield over the arch portion thereof.

In Fig. 7, I have shown another modification in which hard inserts are employed, but in this instance the inserts 19 are in the form of double headed plugs which are entered through the material of the arch after the manner of rivets, and protrude on the outside in the form of rounded bosses which afford non-frictional points of contact to assist in slipping the wearer's arm into the coat sleeve, and at the same time to assist in the ventilation of the shield. As shown in Fig. 7, the continuity of the ribbing on the sides of the shield is interrupted over the arch, and the inserts are there arranged in staggered relation and are interspersed by the apertures 12, although the inserts and apertures might be otherwise relatively arranged without material variation in the nature of the invention.

The shield, in all of the forms illustrated, is intended to afford sufficient resistance to collapse in the arch portion thereof to maintain the circulation of air through the apertures, so that no heating or discomfort will occur by reason of the employment of rubber or similar non-absorbent material of a character impervious to the passage of air. Furthermore, by molding the shield as a whole, its proper shape will be maintained, particularly throughout the arch portion, so that the perforations will not become displaced or overlapped in such a way as to prevent the performance of the ventilating function for which they are intended. In cases where the ribbing is employed, additional stiffening is afforded, particularly in the arch portion, and by making the ribs continuous throughout, air channels are maintained throughout the region beneath the arm pit, so that the tendency to perspire is reduced and the comfort of the wearer insured.

Although it is desirable in molding the shield to afford sufficient thickness of rubber or similar material to render the shield self-sustaining throughout the arch portion, it is not desirable to render the shield unduly stiff or rigid, or otherwise to afford any impediment to freedom of movement of the wearer's arms, or to make the shield sufficiently stiff to in any way prove uncomfortable.

I claim:

1. A shield of the character described, formed of moisture proof rubberlike material and shaped to provide side flaps and a connecting arch portion, and the shield having formed on its outer surface a plurality of ribs continuously extending up one side and over the arch and down on the other side to furnish air channels and to reinforce the arch portion of the shield against collapse.
2. A shield of the character described, formed of moisture proof rubberlike material and shaped to provide side flaps and a connecting arch portion, and the shield having formed on its outer surface a plurality of ribs continuously extending up one side and over the arch and down on the other side to furnish air channels and to reinforce the arch portion of the shield against collapse, the shield being provided with rows of perforations between the ribs.
3. A shield of the character described, formed of moisture proof rubberlike material and shaped to provide side flaps and a connecting arch por-

tion, and the shield having formed on its outer surface a plurality of ribs continuously extending up one side and over the arch and down on the other side to furnish air channels and to reinforce the arch portion of the shield against collapse, the shield being provided with rows of perforations between the ribs, said rows including perforations through the arch portion of the shield between the ribs.

4. A shield of the character described, formed of moisture proof rubberlike material molded to provide side flaps and a connecting arch, the shield being provided with vertically extending spaced ribs, each rib extending continuously up one side and over the arch and down on the other side to reinforce the arch portion of the shield against collapse, and the arch portions of the ribs being afforded by relatively hard smooth inserts to reduce friction.

5. A shield of the character described, formed of moisture proof rubberlike material molded to provide side flaps and a connecting arch, the shield being provided with vertically extending spaced ribs, each rib extending continuously up one side and over the arch and down on the other side to reinforce the arch portion of the shield against collapse, and the arch portions of the ribs being afforded by relatively hard smooth inserts to reduce friction, the shield between the ribs being provided with rows of perforations.

6. A shield of the character described, formed of moisture proof rubberlike material molded to provide side flaps and a connecting arch, the shield being provided with vertically extending spaced ribs, each rib extending continuously up one side and over the arch and down on the other side to reinforce the arch portion of the shield against collapse, and the arch portions of the ribs being afforded by relatively hard smooth inserts to reduce friction, the shield between the ribs being provided with rows of perforations extending through the side flaps and through the arch portions of the shield.

7. A shield of the character described, formed to provide side flaps and a connecting arch, the arch being provided with relatively hard smooth outstanding inserts affording intervening channels over the arch.

8. A shield of the character described, formed to provide side flaps and a connecting arch, the arch being provided with relatively hard smooth outstanding inserts, affording intervening channels over the arch and the arch portion of the shield being provided with perforations interspersed between the inserts to facilitate ventilation in conjunction therewith.

9. A shield of the character described, formed of moisture proof rubberlike material molded to provide side flaps and a connecting arch, the arch being provided withoutstanding protuberant inserts formed of relatively hard smooth material affording intervening channels over the arch.

10. A shield of the character described, formed of moisture proof rubberlike material molded to provide side flaps and a connecting arch, the arch being provided with outstanding protuberant inserts formed of relatively hard smooth material affording intervening channels over the arch, and the arch portion of the shield being provided with perforations interspersed between the inserts.

HUGH G. DUGAN.
